UNITED STATES PATENT OFFICE.

MICHAEL J. KELLY, OF OCEAN VIEW, CALIFORNIA.

PIPE-CO尤LING.

1,254,238.

Specification of Letters Patent. Patented Jan. 22, 1918.

Application filed October 9, 1917. Serial No. 195,617.

To all whom it may concern:

Be it known that I, MICHAEL J. KELLY, citizen of the United States, residing at Ocean View, in the county of San Francisco, State of California, have invented a new and useful Pipe-Coupling, of which the following is a specification in such full and clear terms as will enable those skilled in the art to construct and use the same.

10 This invention relates to a pipe sleeve for use on railway cars to prevent the pipe systems from being dislodged or broken when the cars are coupled and uncoupled.

It will be understood by those skilled in 15 the art that both freight cars and passenger cars are heavily jarred during the coupling and uncoupling and during the operation of the trains. The result of this is that the brake pipes and train signal pipes which are 20 commonly suspended beneath the cars are frequently broken loose from their securing means, and either drop down on the track, or become inoperative because of breakages.

It will be understood that, while the pipe 25 coupling has been especially referred to in connection with train pipes and such uses, it may be equally well used in conjunction with any pipe system which requires such a support as is herein contemplated.

30 Other objects of the invention will appear as the description proceeds.

An embodiment of the invention is shown in the drawings in which the same reference numeral is applied to the same portion 35 throughout, but I am aware that there may be modifications thereof.

Figure 1 is a perspective view of the pipe sleeve showing the means for securing it to the car,

40 Fig. 2 is a longitudinal section of the sleeve, and

Fig. 3 is a transverse vertical section of the sleeve showing the securing means in section as well.

The numeral 1 indicates the sleeve which 45 has threads for the reception of the pipe as indicated at 2 and 3. One side of the sleeve is flat as indicated at 4, and it is provided with a broad groove, as indicated at 5 as well as a groove across the flat side, as indicated at 6, for the purpose of holding the securing means. A heavy flat plate 7 fills the groove on the flat side of the sleeve, and a clamp plate 8 is seated in the curved portion of the groove in the sleeve and suitable 50 screws or bolts 9 and 10 are used to secure the plates and the sleeve in place against the inside of the car frame.

It will be observed that, before the sleeve can be unshipped from its securing means, 60 the plate 7 must be forced off its bolts, and owing to the flat base of the sleeve it is possible to assemble the pipes therein when the sleeve has been fastened in place under the car frame, since the flat portion of the sleeve 65 prevents it from being rotated when the clamp 8 has been secured in place.

Having thus described my invention, what I claim as new and desire to secure by Letters Patent of the United States is as follows, express reservation being made of permissible modifications:

A threaded pipe sleeve having a circumferential groove around its central portion and a flat base, a flat plate upon which the 75 sleeve rests and which fits said groove, and a clamp fitted into the groove around the sleeve, the flat plate and clamp adapted to secure the sleeve to an object.

In testimony whereof I have hereunto set 80 my hand this 2nd day of October, A. D. 1917.

MICHAEL J. KELLY.
